Inventor,
William Houston,
by L. S. Hammann Atty.

UNITED STATES PATENT OFFICE.

WILLIAM HOUSTON, OF HAVERHILL, MASSACHUSETTS.

PIE-PLATE ATTACHMENT.

Application filed November 7, 1927. Serial No. 231,559.

This invention relates to certain improvements in attachments for the rims of pie plates when used for baking pies having a soft, or liquid filling, and, more particularly, to certain improvements on the type of attachment shown in my prior Patent No. 1,640,409, in which a fluted ring is secured within a flat metal ring and seats on the plate rim, the flat metal ring being of greater internal diameter than the periphery of the plate rim and depending about the rim to hold the attachment in position.

While the construction above referred to operates satisfactorily, so far as performing its intended function is concerned, at times the dough, or filling of the pie overflows the top edge of the fluted ring and passes down between the same and the outer ring and becomes baked therein, so that it is difficult to remove, and this has been found to be an objection.

The objects of my invention are to provide a construction having all the practical advantages of my said prior construction, but which permits ready separation of the rings for cleaning purposes, and equally ready replacement thereof.

I accomplish these objects by means of the construction hereinafter described and illustrated in the accompanying drawing, in which:—

Fig. 1 is a plan view of an attachment embodying my invention.

Fig. 2 is a sectional view at line 2—2 of Fig. 1, on an enlarged scale.

Fig. 3 is a similar view of a slightly modified form of the invention.

Figs. 4 and 5 are detail views of sections of the member of the attachment.

In the drawing, a circular plate *a* having an approximately flat rim portion *b*, is illustrated, to which type of plate the attachment is primarily intended to be applied.

According to my present invention, a ring *c*, formed of a strip of flat sheet metal, is provided having its end portions rigidly secured together in any suitable manner, and having an inwardly projecting bead *d* in the middle thereof which extends throughout its length, and provided oppositely facing shoulders on its inner side. In practice

the bead will be formed in the material while it is in strip form, and when the ends of a section of the strip are connected, to form an attachment for a plate having a rim periphery of certain diameter, the internal diameter of the ring portions at each side of the bead will be slightly greater than the diameter of the rim, to permit said portions to pass easily thereon, while the internal diameter of the bead portion will be somewhat less than the rim diameter, so that, when the ring is placed over the plate rim one of the shoulders formed by its beaded portion will engage the top side of the rim and the ring will be supported thereon.

I further provide a transversely fluted ring *e*, which is also formed of a strip of sheet metal and is of such external diameter that it may be removably fitted into the ring *c*, so that one edge thereof will either engage and rest on the bead *d*, as shown in Fig. 2, or, if made of slightly less diameter, will fit within the beaded portion and rest directly on the plate rim when in use, as shown in Fig. 3.

The portions of the ring *c* at each side of the bead are of cylindrical formation and of equal diameter so that it is immaterial in practice which edge portion is placed about the plate rim and which edge portion receives the fluted ring.

With the above described construction, the two rings will be placed, one within the other and set on the plate ring and the dough will be built up against the fluted ring, as described in my said prior patent, and after the baking operation has been performed the rings will be removed and separated for washing purposes, if desired.

I claim:

1. A pie plate attachment comprising a flat metal ring having one of its edge portions of greater internal diameter than the diameter of the periphery of the plate rim in connection with which it is to be used, and having an intermediate inwardly projecting and circularly extending shoulder adapted and arranged to rest on the rim to support the ring thereon, and a transversely fluted ring removably fitted within the opposite portion of said flat metal ring.
2. A pie plate attachment comprising a

- flat metal ring having its edge portions of greater internal diameter than the greatest diameter of the rim of the plate in connection with which it is to be used, and having
- 5 an intermediate internally projecting bead of less internal diameter than said plate rim and adapted to engage the same to support
- the ring thereon, and a fluted metal ring of less external diameter than the said edge portion of the flat metal ring and adapted 10 to be removably fitted therein.

In testimony whereof, I have signed my name to this specification.

WILLIAM HOUSTON.
